UNITED STATES PATENT OFFICE.

ALBERT BONHAM MUELLER, OF RUNGE, TEXAS.

DEEP AND SHALLOW WELL CYLINDER PROTECTOR.

Application filed July 5, 1923, Serial No. 649,556. Renewed May 29, 1926.

This invention relates to protectors especially adapted for use in shallow and deep wells and are used for the protection of working or cylinder barrel and parts.

5 An important object of this invention is to provide reliable means for preventing the accumulation of fallen and settling rust, scale, sand, clay, sticks, etc., in the working barrel and consequently interfering 10 with the operation of the plunger and valves therein, the said means being coupled onto the upper working barrel cap and may also be engaged in the upper end of the working barrel; said means being interchangeable and may also be engaged in a 15 protector barrel, protector barrel to be used in upper end of deep well cylinder or working barrel; said protector may be used as a screen below the working barrel seat 20 valve.

Furthermore the invention aims to provide simple means for preventing foreign matter such as sand, etc., from being pumped up into the working barrel and 25 causing the cups and the interior of the working barrel to wear rapidly and also to prevent the clogging of plunger and seat valves, and scarring of working barrel.

30 A further object of the invention is to provide a protector of the character specified which is of highly simplified construction, cheap to install and durable in use.

Other objects and advantages will be apparent during the course of the following 35 description.

In the accompanying drawing forming a part of this application and in which like numerals are employed to designate like parts throughout the same.

40 Figure 1 is a side elevation of the improved protectors applied.

Figure 2 is a vertical sectional view through the improved protectors applied.

45 Figure 3 is a detail vertical sectional view illustrating the means for securely holding the protectors in a set position above the cups.

Figure 4 is a side elevation of protectors especially adapted for use in deep wells, 50 the protector being located within the working barrel of the well equipment.

Figure 5 is a vertical sectional view 55 through the protectors illustrated in Figure 4, the protectors in this view being illustrated applied.

Figure 6 is a detail sectional view through a closure cap embodied in the invention.

Figure 7 is a side elevation of a protector adapted to be arranged above the working barrel and interposed in the tubing. 60

Figure 8 is a sectional view through the protector illustrated in Figure 7.

Figure 9 is a vertical sectional view 65 through a working barrel adapted for connection at its upper end to one of the protectors and a protector-strainer connected to its lower end.

Figure 10 is a side elevation of a modified form of an interchangeable protector 70 adapted to be arranged above the working barrel so as to protect the working barrel, cups and valves therein from falling rust and the like.

Figure 11 is a vertical sectional view 75 through the protector illustrated in Figure 10.

In the drawing the numeral 15 designates an interchangeable perforated or incisioned tube which as illustrated in Figure 1 is mounted between upper base 20 and lower base 20^A and has its ends engaged over upper and lower nipples 17 and 18 respectively. The nipples 17 and 18 are in turn threaded into upper and lower base members 20 and 20^A, the said base members being connected by means of brace rods 22. Figure 2 clearly illustrates that the upper member 20 is provided with set screws 24 which engage the brace rods and thereby securely hold the same in position, also it will be noted that the sucker rod 16 operates through stuffing box gland or rod guide 29. 85

With particular attention to Figure 3 it will be noted that the lower base member 20^A is provided with a series of radial sockets for the reception of holding lugs 25 which are engaged by cap screws 26. The inner ends of the lugs are beveled so that when the cap screws 26 are advanced the lugs will be moved outwardly into engagement with the inner sides of the working barrel 27. In this manner the protector may be securely and positively held in a desired position within the working barrel. Base 20^A is interchangeable on either protector tube or strainer when used as a protector as shown in my invention. 100

105 A threaded collar 28 is connected to the upper base 20 and engages a gland 29 so 110

as to hold the same securely in position; it will be seen that the gland 29 constitutes a guide for the sucker rod 16, also gland 29 holds stuffing box packing in position and also prevents fallen matters from entering the working barrel through the protector.

The lower portion of the sucker rod 16 is provided with the usual plunger complete consisting of cup leather 30, valve cage bracket 32 and valve 33, seated on plunger base, which have a working fit in the working barrel and on the upstroke draw in a quantity of liquid through valve 37. The 10 cups are carried by the usual cage 32 suspended from the sucker rod 16 and a valve 33 located within the cage 32, seated on plunger base. In summarizing it will be seen that falling and settling rust, scale, sand, clay, sticks, etc. through and from the pump tubing 34 and from sucker rod 16 are prevented from settling in working barrel 27 on the cups 30 and valves 33 and 37 by the protector tube 15 and its associated elements. In this 15 manner scarring of the cylinder or working barrel 27, cups 30 and valves 33 and 37 and valve seats, rapid wear on the cups 30, blocking of the seat valve 37 and plunger valve 33 and serious damage to the same is 20 prevented; also the lower base member 20^A prevents the sediments and the like from entering the working barrel 27 below base 20^A, which does not pulverize from the friction caused by the pumping of liquid 25 through protector tube 15 or similar perforated tube.

The lower portion of the working barrel has a seat valve 37 of any desired construction, which seat valve 37 allows the oil, water, etc. to enter the working barrel 27 and prevent the return of the same. The lower portion of the nipple 31 is provided with a protector interchanged, used as a strainer, perforated strainer tube 39 which 40 is surrounded by gauze wire 40 or the like. The oil, water, etc. enter by the way of the gauze wire 40 and the like, and protector tube used for strainer tube 39 through the nipple 31 and into the working barrel 27 45 by the way of seat valve 37. It is here noted that tubes, copper and brass cloth of any desired size perforation and gauze wire of any desired mesh may be employed, this feature being merely a matter of choice or 50 discretion on the part of the operator to combat falling and rising sediments. The lower portion of the perforated tube 37 is closed by a disc 41 confined between upper and lower fastening member base 42 and base collar 43 respectively, the upper fastening base member 42 being threaded onto the lower portion of the tube 39.

In the form of the invention illustrated in Figures 4, 5 and 6 the protecting member 55 is in the nature of a coiled spring 50, the

convolutions of which are rather close together so as to prevent the falling and settling of sediments, rust, scale, taps, sticks, sand, clay and the like, into the pump tubing and sediments from liquid being pumped through the convolutions of the coiled spring protector 50 from entering and settling within working barrel 59 on the cups 60 and valves 61 and 65. The pressure from the forcing of liquid through the convolutions of the coiled spring 50 causes the spring to expand and open sufficiently to allow passage of the liquid drawn up with the sucker rod 63 and its associated elements. As the sucker rod travels on the downward stroke the pressure from the liquid is exhausted and the convolutions of the coiled spring 50 close to its original position, which prevents sediments and the like from entering the working barrel 59 through the interior of the coil. Also the coiled spring 50 is used for the pumping of liquid of a heavy consistency. The coiled spring is somewhat tapered towards the outer side at its lower end so as to be easily fitted on base 54^A and held in position with nut 53 slipped down on the coiled spring and threaded upon base member 54^A. Also the coiled spring 50 is somewhat tapered towards the inside at its upper end so as to prevent the gland 54 from drawing through the upper end of coiled spring 50 when the nut 51 is threaded upon the gland 54 to hold the coiled spring protector in position; also the coiled spring deflects rust, scale, taps, sticks, and the like and prevents the clogging on account of pressure, expanding, and the convolutions of the spring automatically closing.

Figure 5 illustrates that the ends of the coiled spring 50 are held in position by means of nuts 51 and 53, the nut 51 being threaded on a gland 54, while the nut 53 is threaded upon a base member 54^A. The lower cap 55 of the protector barrel 56 has threaded engagement with the protector base member 54^A and supports the same within the protector barrel 56. The upper portion of the protector barrel 56 is provided with a pronged cap 58 by means of which the protector barrel 56 and its associated elements can be drawn out of working barrel 59 and through pump tubing, which pronged cap 58 prevents hanging within joints, etc., when drawn out through pump tubing with sucker rod 63. Also the pronged cap 58 prevents the protector barrel 56 from entering further into the working barrel 59. The protector barrel 56 is located within the upper portion of the working barrel 59, the pronged cap 58 threaded into the upper end of protector barrel 56, the outer edge of the cap 58 extends over protector barrel about (3/2) three-thirty-seconds of an inch that gives the protector a seated position on the upper end 130

of the working barrel 59 and prevents the sediments from entering working barrel 59 (between working barrel 59 and protector barrel 56). The important feature of the 5 protector barrel 56 and its associated elements are; that it prevents the falling and settling matters from entering the interior of the working barrel 59, the scarring of working barrel, cups, valves and valve seats 10 and the blocking of same, also rapid wear to the same is prevented. The usual cup 60, the valve 61, the cage 62 and the cage base are connected to sucker rod 63 and operates within the working barrel 59 as the 15 cups 60, the valve 61, the cage 62 and the cage base is located within working barrel 59 below the protector's lower cap 55; the said protector positively prevents falling objects and sediments from interfering 20 with the operation of the traveling valve 61 and cups 60. Also the protector prevents matters from interfering with the operation of the valve 65 of the standing valve 63^A mounted on the seat cap 64 in the 25 lower portion of the working barrel 59. A valve 65 constitutes a part of the standing valve 63^A and is disposed within the usual cage 66 seated on the standing valve base. Seat valve 65 allows oil, water, etc., to enter 30 the working barrel 59 and prevents the return of the same.

In carrying out the invention a protector closed by a disc, interchanged to a strainer. A strainer tube 68 is threaded into the standing valve base 63 and is provided with a series of arcuate incisions by means of which the liquid is permitted to enter. The incisions in the tube 68 may be extended diagonally or otherwise and are sufficiently narrow to prevent the entrance of undesirable matter. The lower portion of the strainer tube 68 is closed by a disc 70 confined between upper and lower attaching members 72 and 73, the attaching member 72 being 40 threaded onto the strainer tube 68 while the attaching member is threaded onto the member 72.

It might be stated that these protectors, strainers and screens are interchangeable for 50 the purpose of protecting the working barrel and its associated elements from the top and bottom for shallow and deep well cylinders of any make and size required. The protector may be attached within the upper portion of the working barrel with a base member 20^A or above the working barrel cap within a protector tube connected to pump tubing. A protector when seated 55 within the upper portion of a deep well cylinder barrel with the sucker rod operating through its base gland is removed from the working barrel by drawing the sucker rod with its fittings and replaced in its original 60 position. A coupling connected with the 65 sucker rods operating above the protector

base gland is used to seat the protector within its stationary position in the upper portion of working barrel when found necessary.

It might be stated that protectors of any 70 form and size can be used in wells where found necessary to the falling matters, formations and sediments which may enter by way of pump tubing and rise with the water, oil, etc., to prevent clogging of the 75 protector attached below cylinder, and the blocking of the cylinder parts and allow liquid to pass through the protectors, the working barrel and upper protector. Also the protector used above the working parts 80 of working barrel must have larger sized openings than the strainer below the working parts to allow sediments drawn in through strainer to pass freely through the 85 upper protector with liquid to prevent the working parts from blocking with sediments.

The protector illustrated in Figures 7 and 8 consists of a tube 80 the upper portion of which has a reducer 91 which has connection for pump tubing, the lower portion of the protector tube 80 being connected with a reducer (same as reducer 91) with a nipple 81 threaded within, adapted to be threaded in the cap 82 of the working barrel 83. It is thus seen that the protector 80 is located 90 above the working barrel 83 and consequently prevents falling matters and sediments from entering the working barrel.

Referring again to Figures 7 and 8 it 100 will be seen that a small tube 84 is arranged within the protector tube 80 and threaded into the lower reducer same as 91 and formed with a series of openings 85 for the free passage of the oil, water, etc. A screen 86 is extended about the small tube 84 and the openings 85 therein so as to prevent foreign and settling matters from dropping through the openings 85.

In carrying out this form of the invention 110 a sucker rod 88 is passed through the tube 80, gland base 89, small protector tube 84 and nipple 81 into working barrel 83 threaded into cage with its working fit. The gland base 89 is carried by the upper 115 portion of the small tube 84. A reducing member 91 is threaded onto the upper end of the tube or working barrel 80 and adapted for connection with the lower portion of the pump tubing.

When the sucker rod 88 is threaded into 120 the plunger valve cage then the nipple 81 is threaded into the cap 82. The protector barrel 80 and the working barrel 83 form a rigid construction below which a strainer member 94 is located and of course the lower portion of the protector member 94 may be closed by means of a closure 96 similar in construction to the members 70, 72 and 73.

A modified form of protector is illustrated 130 in Figures 10 and 11 wherein the outer pro-

TECTING tube 100 has its upper end provided with a cap 101 adapted to be threaded onto the lower end of the pump tubing; also the lower portion of the outer protecting tube is provided with a cap 102 with which a nipple 103 is connected. The nipple 103 is in turn threaded onto the cap 82 of Figure 9, so as to mount the protector above the working barrel 83. A sucker rod 105 operates up and down through the gland 112, also packing must be used within gland seat when necessary. The sucker rod 105 is extended through the pump tubing and the perforated tube 106 and its associated elements into the working barrel 83 and threaded into valve cage within working barrel 83. The tube 106 is formed with a series of diagonal incisions 107 formed by sawing or otherwise. The upper portion of the tube 106 is formed with a base 110 with which a threaded collar 111 is engaged and forms a means to hold the gland 112 in position, which gland acts to guide the sucker rod 105 and prevent the entrance of materials into the tube 106. It will be seen that the improved protector forms an efficient means for preventing objects from settling, scarring and lodging on the cups and valves and interfering with the operation of the same. The inventive idea involved in this application may be carried out in shallow and deep well cylinder protectors of any form and size for shallow or deep well cylinders of any size, construction or arrangement.

In operation, various types of interchangeable protectors, strainers and screens may be employed to combat, sand, clay, rust, sticks and the like from entering the working barrel and to protect the parts of the working barrel, the working barrel and the cups and valve leathers. The openings in the various strainers and screens may be either large or small according to the formation and sediments within which the same are located and the gravity of the fluid pumped.

The foregoing illustrates that this invention is capable of a wide variety of mechanical expressions and it is therefore to be

understood that such minor changes in arrangement and construction of parts may be made as will remain within the spirit of the invention and the scope of what is claimed. 50

Having thus described the invention, 55 what is claimed is:—

1. In combination with a working barrel, and a plunger operating therein, a protector within the upper part of the barrel and comprising a hollow body consisting of a 60 spring coil, means for closing the upper end of the coil, the lower end of the interior of the coil communicating with the interior of the working barrel, the convolutions of the coil being closely adjacent to prevent sand, scale, sticks and the like falling onto the plunger in the working barrel, the spaces 65 between the convolutions providing openings transversely of the hollow body to permit discharge of water from the working 70 barrel.

2. In combination with a working barrel, a plunger operating therein and a sucker rod for actuating the plunger, a protector comprising a protector barrel fitted within 75 and mounted on the upper end of the working barrel, the protector barrel being entirely contained within the working barrel, a hollow body arranged and entirely contained within the protector barrel, said hollow 80 body having openings transversely thereof along its entire length, means for closing the upper end of the hollow body, said means having an opening in which the sucker rod is slidably fitted, the hollow body having an 85 opening in its lower end affording communication between the interior of the hollow body and the space within the working barrel in which the plunger operates and also affording a clearance for accommodat- 90 ing the sucker rod, the outer periphery of the hollow body being spaced from the inner periphery of the protector barrel, and means for closing the space between the lower end of the hollow body and the lower 95 end of the protector barrel.

ALBERT BONHAM MUELLER.
